CARRYING CASE

Robert H. Larson, Batavia, Ill., assignor to Dukane Corporation, St. Charles, Ill., a corporation of Illinois

Application April 13, 1959, Serial No. 55,530

Term of patent 14 years

(Cl. D87—5)

The dominant features of my design reside in those portions shown in full lines on the drawing.

I claim:

The ornamental design for a carrying case, substantially as shown and described.
